UNITED STATES PATENT OFFICE.

FRED L. BABB, OF LYNN, MASSACHUSETTS.

SHUTTLE FOR SEWING-MACHINES.

SPECIFICATION forming part of Letters Patent No. 724,652, dated April 7, 1903.

Application filed July 23, 1902. Serial No. 116,663. (No model.)

To all whom it may concern:

Be it known that I, FRED L. BABB, a citizen of the United States, residing at Lynn, in the county of Essex and State of Massachusetts, have invented certain new and useful Improvements in Shuttles for Sewing-Machines; and I do hereby declare the following to be a full, clear, and exact description of the invention, such as will enable others skilled in the art to which it appertains to make and use the same.

The present invention relates to shuttles for sewing-machines.

The object of the present invention is to provide a simple and efficient friction device for the cop which shall cause a resistance to rotation of the cop substantially proportional to the diameter of the cop, so that the tension on the thread shall be practically constant, no matter whether the cop be full or partially exhausted.

Another object of the present invention is to produce a friction device for the cop which will have no tendency to abrade or entangle the thread.

A still further object of the present invention is to provide a friction device which shall engage the cop directly and produce a smooth and even friction with a minimum of pressure.

With these objects in view the present invention consists of the devices and combinations of devices hereinafter described and claimed.

Heretofore in the art it has been found most desirable to employ in connection with shuttles of sewing-machines a cop of thread supported upon a cop-tube of paper or pasteboard, and many shuttles have been devised in which

these cops could be used directly without the necessity of rewinding the thread upon a bobbin of peculiar size and shape to fit the shuttle. Whether these cops be used directly or whether the thread must be rewound upon a

bobbin it has been found necessary to employ a friction device of some sort to prevent the bobbin or cop from overrunning, and thus snarling or entangling the thread. When the cop is used directly in a bobbin-case, it has

been the practice to employ a friction device of spring metal which is interposed between the bobbin-case and the cop and by its yield-

ing pressure produces sufficient frictional resistance to prevent overrunning of the cop in the bobbin-case. These metallic friction devices, however, have been found objectionable for several reasons. They are uncertain in action, as sometimes they rotate with the cop while at others they are held by the bobbin-case, the frictional resistance of the cop to rotation thus varying considerably, according to whether the sliding contact is between the thread and the metallic friction device or between the metallic friction device and the metallic bobbin-case. Moreover, the thread is liable to be abraded or entangled by the spring-arms of such devices. When these metallic friction devices are located within the bobbin-case, they are necessarily very small, and if for any reason they are slightly bent or twisted, as is often the case, their operation is interfered with. These metallic spring friction devices wherever they have been employed in direct engagement with the cop have been so constructed that the surface of contact on the cop was a narrow circular band adjacent the cop-tube. Whether such a friction device rotates with the cop or is held by the bobbin-case the resistance to rotation of the thread-cop is substantially constant irrespective of whether the cop be full or partially exhausted. Less tension on the thread, therefore, is required to draw it off when the cop is full than when it is partially exhausted, since the resistance is substantially constant, while the radius or leverage is much greater in the former case than in the latter. None of these devices of the prior art, therefore, can produce uniform and unvarying tension on the shuttle-thread, so necessary for perfect sewing.

In the present invention I have provided a simple and efficient friction device which overcomes all these objectionable features inherent in the friction devices of the prior art and which is applicable, among others, to the shuttles of the Singer C. B., Singer I. M., Singer large flat bobbin, Wheeler & Wilson D. 12, the several Wheeler & Wilson vertical-hook machines, and the Standard sewing-machine.

In the accompanying drawings, Figure 1 is a side elevation of a shuttle embodying my invention; and Fig. 2 is a vertical section on

line 22, Fig. 1, looking in the direction indicated by the arrows.

1 represents the shuttle, which is provided with the pin or stud 2.

5 3 is the bobbin-case, having the cylindrical tube or bearing 4, which supports the bobbin-case upon the pin 2 of the shuttle. The cop 5 upon the paper or pasteboard cop-tube 6 is supported upon the tube or bearing 4 of the 10 bobbin-case with a loose fit.

15 7 is my improved friction device, which consists of felt or some other elastic fabric. This felt is in the form of a washer surrounding the tube or bearing 4 of the bobbin-case and 20 closely fitting the interior of the bobbin-case, so that it is held from rotation with the cop. The felt washer directly engages the thread-cop with a light yielding pressure, which by the nature of the two contacting surfaces results in a smooth and even resistance to 25 rotation on the part of the cop. Since the felt washer engages one entire end of the cop, the resistance to rotation of the cop will be greater the greater the diameter of the cop; but since 30 the effective distance through which the pull on the thread is exerted is the radius of the cop these two factors will balance each other, and the tension on the thread necessary to draw off thread from the cop will be uniform 35 and unvarying no matter what the diameter of the cop may be.

It will be noted in this connection that 40 since the felt washer fits tightly within the bobbin-case it cannot rotate with the cop, which would result in a markedly-diminished resistance through the sliding of the felt on the metal. Moreover, there are no spring arms or points to abrade or entangle the thread, thus avoiding the necessity of stopping the sewing-machine and the loss of time and waste of thread.

Although in Fig. 2 of the drawings the latch

is shown for holding the bobbin-case within the shuttle, I have not described the same, as it forms no part of the present invention.

Having thus described my invention, I claim as new and desire to secure by Letters Patent of the United States—

1. A sewing-machine shuttle, having, in combination, a shuttle, a bobbin-case constructed to receive a cop of thread from the outside of which the thread is unwound by rotation of the cop in the case, and a washer of elastic fabric located in the bobbin-case and bearing frictionally upon the end of the 50 cop to control its rotation in the bobbin-case, substantially as described.

2. A sewing-machine shuttle, having, in combination, a shuttle, a bobbin-case constructed to receive a cop of thread from the outside of which the thread is unwound by rotation of the cop in the case, and a washer of elastic fabric located within the bobbin-case and held from rotation therein said washer bearing frictionally upon the end of the 65 cop to control its rotation in the bobbin-case, substantially as described.

3. A sewing-machine shuttle, having, in combination, a shuttle, a bobbin-case constructed to receive a cop of thread from the outside of which the thread is unwound by rotation of the cop in the case, and a washer of elastic fabric located within the bobbin-case and fitted tightly thereto, said washer bearing frictionally upon the end of the cop 75 to control its rotation in the bobbin-case, substantially as described.

In testimony whereof I affix my signature in presence of two witnesses.

FRED L. BABB.
